UNITED STATES PATENT OFFICE

DANIEL LAWRENCE BRAINE, OF BROOKLYN, NEW YORK, ASSIGNOR TO THE RAIL JOINT COMPANY, OF NEW YORK, N. Y., A CORPORATION OF NEW YORK

COMPROMISE RAIL-JOINT BAR

Application filed June 5, 1929. Serial No. 368,609.

This invention relates to compromise or step join bars for connecting and holding the ends of rails of different sections with the gage and surface of the rails in alinement, and has far its general object to provide a highly efficient bar of this type which is capable of being produced by an economical forging operation.

More particularly, it is a purpose of the present invention to provide a compromise rail joint bar of the general type disclosed in Armstrong Patent 1,663,619, involving a balanced distribution of metal in the head and foot portions thereof and having a truncated or cut-off foot flange to provide a toeless formation which overlies the rail flange. Also to provide a medial reinforcement which substantially strengthens the bar in the lower chord of the girder where added strength is required due to the absence of the usual foot flange of the bar. Furthermore, the invention has in view to utilize these desirable features in a bar which has its loading engagement with the head fillet of the rail, as in the so-called "headfree" type of rail joint.

By making the bar of a toeless formation the construction of the forging dies is greatly simplified, and their cost is minimized, due to the number of angularly related surfaces constituting the die impressions being minimized. Moreover, by this construction all spike slotting problems are eliminated.

Due to the hammer clearance which must be provided between the dies and to the wear of the dies in the fishing fit, it is apparent that after a number of bars have been formed by a set of dies in which each die includes both fishings, as is the practice, proper fit of the bar fishings with the rail fishings becomes increasingly difficult to obtain. However, by forming the present bar with rail-head clearance, that is, of the headfree type, the same will satisfactorily fit the rails irrespective of any slight inaccuracies in the fishing surfaces of the bar. Also, by forming the bar of this head-free type, the dies may conveniently be parted at the outer fillet of the head of the bar so that merely rough trimming of the flashings produced at this point as a result of the forging operation is all that

is necessary, since with the head-free construction, any slight projection at the outer fillet of the head of the bar will not interfere with the fit of the bar with the rail fishing surfaces.

By forming the bar with a substantially equal distribution of metal in the head and foot thereof, the bar may readily be forged from a flat or rectangular shape, as the metal will easily distribute itself in the dies. This also greatly facilitates the cooling of the bar by eliminating warping and twisting thereof, and facilitates heat treating of the bar inasmuch as the substantially uniform section of the bar permits an even penetration of heat.

Reinforcing the bar at the point of junction of the high and low fishing sections thereof provides strength where the bar ordinarily would be weakened by vertically and laterally offsetting same to provide the low fishing section thereof. In accordance with the present invention said reinforcement is disposed so as not to interfere with proper engagement of the bar with the rails, nor with seating of the rails on the ties, and is so placed and formed as to provide added reinforcement in the lower chord of the bar-girder to compensate for the absence of the usual extended foot flange formation.

In describing the invention in detail, reference will be had to the accompanying drawings, wherein:

Fig. 1 is a perspective view of a compromise rail joint constructed in accordance with the present joint bar.

Fig. 2 is a side elevation of the rail joint shown in Fig. 1.

Fig. 3 is a transverse section on the line 3-3 of Fig. 2.

Fig. 4 is a transverse section on the line 4-4 of Fig. 2; and

Fig. 5 is a transverse section on the line 5-5 of Fig. 2.

Similar reference characters designate corresponding parts in the different figures of the drawings.

As previously stated, the present bar, designated generally as A, preferably is a forged product, and consists of a high fishing section H to fit the high rail R of the step joint com-

bination of rails with which the bar is intended for use, and a low fishing section L vertically and laterally offset with respect to the high fishing section, to fit the low rail R of the rail combination. Also, each of the sections H and L of the bar preferably consists of a head 10, a web 11 and a foot 12. Preferably the head 10 is provided throughout its length with an outer reinforcing rib 13.

10 In accordance with the present invention the bar A is of toeless formation in the sense that no part of either the high or the low fishing section thereof projects beyond the outer edge of the flange of its related rail.

15 However, a narrow stiffening flange 14 extends outwardly from the foot 12 of each section of the bar to afford a spike head bearing surface, this abbreviated flange terminating preferably slightly inwardly of the outer

20 edge of the rail flange whereby the necessity of slotting said portion for the reception of spikes is avoided, and whereby free "running" of the rails without impairing the joint, and without imposing shearing stress on the

25 spikes, is permitted.

Each section of the bar is of head-free construction, that is, a clearance 15 is provided between the under side of the head of the rail and the top surface of the head of the bar, and

30 the said head of the bar has a loading engagement or bearing only at the head fillet of the rail. Moreover, the upper and lower halves of each section of the bar are formed with a substantially balanced distribution of

35 metal to compensate for any weakness resulting from truncating the conventional foot flange with its toe to make the bar of the so-called toeless type with its abbreviated flange

14.

40 The reinforcement 16 at the junction of the high and low fishing sections H and L is disposed entirely within the upper and lower limits of the outer contour of the bar and between the two inner bolt holes. Said reinforcement is preferably in the form of a rib or enlargement of any desired width, extending from its merger with the head reinforcing rib 13 downwardly and inwardly towards

45 a middle portion of the web 11, and thence outwardly and downwardly towards and merging into the foot flange portion 14. A portion 17 of said reinforcement is formed to overlie the outer edge of the flange of the

50 low rail R' at the end thereof, this portion 17 extending preferably over the inner bolt hole of the low fishing section L to afford additional strength for the toe of the low fishing section of the bar. This reinforcing metal

55 17 is at the outer side of the bar and is in the form preferably of a vertical swell of the foot flange 14 in order to provide added strength and reinforcement to the lower chord of the bar-girder in the vertical plane

65 of the effective reinforcement produced by

the merger of the reinforcing metal with the upper outer rib 13.

From the foregoing description, considered in connection with the accompanying drawings, it is believed the advantages of the present joint bar will be fully appreciated. As before stated the toeless design of the bar permits of same being produced economically by a forging operation; the head-free feature not only affords very satisfactory manufacturing 70 tolerance limits but avoids the necessity of anything more than roughly removing the flashing resulting from parting the forging dies at the outer fillet of the head of the bar, which point of parting the dies has been found highly satisfactory in manufacture of the bar; by providing a substantially balanced distribution of metal in the upper and lower halves of the bar strength is maintained despite elimination of the usual toe, 75 and at the same time the metal will readily distribute itself properly between the forging dies and the cooling and heat treating process is facilitated; and by reason of the special form and specially disposed medial reinforcement 16 with its swell 17 the bar is possessed of material strength and stiffness at the junction of its high and low fishing sections. 80

Without further description it is thought 85 that the features and advantages of the invention will be readily apparent to those skilled in the art, and it will of course be understood that changes in the form, proportion and minor details of construction may be resorted to, without departing from the spirit 90 of the invention and scope of the appended 95 claims.

I claim:

1. A compromise rail joint including the 105 rail, and a bar having a head portion provided at its inner side with a bearing member for engaging the rail head fillet and at its outer side with a longitudinal reinforcing rib, said bar also being provided with a foot portion of toeless formation and having a narrow reinforcing flange longitudinally of the bar and an integral body of reinforcing metal at the outer-side of the bar between the inside bolt holes and integrated with the rib of the 110 bar head and with the flange of the bar foot. 115

2. A toeless compromise joint bar inclusive of a reinforcement at the junction of the high and low fishing sections thereof, said reinforcement being inclusive of a flange disposed within the plane of the outer edge of the flange of the high rail and to overlie the outer edge of the flange of the low rail of the step joint combination of rails with which the bar is adapted for use. 120

3. A compromise rail joint including the rail, a bar provided with a foot portion of toeless formation having a reinforcing rib extending longitudinally of the bar inside 125 the plane of the outer edge of the flange of the 130

high rail, and a body of reinforcing metal integrated with said reinforcing rib and with the web of the bar and disposed substantially within the plane of the outer edge of said rib.

5 In testimony whereof I hereunto affix my signature.

DANIEL LAWRENCE BRAINE.
